O. W. ANDERSON

HOT AIR FURNACE

Filed June 19, 1926

Inventor
Oscar W. Anderson

By Joshua R. H. Dott
Attorney

Patented Dec. 7, 1926.

UNITED STATES PATENT OFFICE.

OSCAR W. ANDERSON, OF IRON MOUNTAIN, MICHIGAN.

HOT-AIR FURNACE.

Application filed June 19, 1926. Serial No. 117,060.

My invention relates to furnaces and particularly to hot air furnaces such as are employed for heating dwellings and other buildings. The object of my invention is to provide a furnace of the character mentioned of such construction and arrangement of parts as to insure a substantially complete combustion of the fuel, thereby obtaining a maximum amount of heat from a given amount of fuel. A further object of my invention is to provide a device of the class mentioned which will emit but little, if any smoke from the flue. Other objects will appear hereinafter.

With these objects in view my invention consists generally in providing a hot air furnace with a combustion chamber terminating at its upper end in an imperforate dome, arranging the flue or smoke pipe so as to terminate a considerable distance below the top of the dome, and providing means for injecting air into the upper portion of the dome so as to supply oxygen to the smoke and gases accumulated in the dome to insure a substantially complete combustion thereof. My invention further consists in arranging the air admission means so as to thoroughly heat the air therein before injecting the air into the dome, and of such construction and arrangement as to avoid pocketing the air, and thereby insuring a constant and steady supply of fresh heated air.

My invention consists in various details of construction and arrangements of parts all as will be fully described hereinafter and particularly pointed out in the claims.

My invention will be more readily understood by reference to the accompanying drawings forming a part of this application.

The figure is a vertical section of a furnace embodying my invention, parts being illustrated in elevation.

Referring now to the drawings, 1 indicates the outer casing from the upper end of which extends the sleeves 2 for connecting the usual heat pipes. 3 indicates the fire pot and 4 the ash pit. Arranged within the casing 1 and spaced therefrom is an inner casing 5 forming the combustion chamber 6 and terminating at its upper end in an imperforate dome 7. 8 indicates the feed door, 9 the door to the ash pit and 10 the draft door. These parts with the exception of the imperforate dome 7 are common to furnaces of this class and may be of any ordinary or preferred construction.

Leading from a point 11 adjacent the center of the combustion chamber is a smoke eduction pipe 12 which passes downwardly from the point 11, through the side of the inner casing 5, preferably just above the fire pot 3, and then downwardly, where it communicates at 13 with a smoke pipe 14 leading to the flue. The bottom end of the smoke eduction pipe 12 passes downwardly below the point of communication with the smoke pipe, forming a soot chamber 15 which is provided with a clean-out door 16.

Leading from the ash pit 4 is an air pipe 17 which passes directly upwardly into the combustion chamber 6 and terminates at 18, at the top of the dome 7 and adjacent the center thereof. It should be noted that the pipe 17 has no horizontal, or substantially horizontal parts, and therefore does not form any air pockets and that by being arranged within the combustion chamber 6 above the fire pot 3, the air passing upwardly therethrough will be highly heated before being injected into the dome 7. It will be noted that the end 18 of the pipe is considerably above the inlet end 11 of the smoke eduction pipe 12.

In operation, the products of the combustion of the fuel in the fire pot 3, consisting of smoke and gases, pass upwardly into the dome 7. These products of combustion are in a highly heated state. Air will pass freely up the pipe 17 and in so passing will be highly heated and injected into the trapped smoke and gases in the dome 7, thereby supplying sufficient oxygen for their complete combustion. In this manner a maximum amount of heat is obtained from a given amount of fuel, and furthermore, the smoke is substantially completely burned, thereby allowing little or no smoke to pass into the flue. It is also obvious that my invention may be applied to any of the ordinary hot air furnaces in general use.

I claim:

1. In a hot air furnace, a fire pot and a combustion chamber terminating in an imperforate dome, means for injecting air into the upper end of said dome, a smoke eduction pipe leading from said combustion chamber below said dome and extending downwardly on the outside of said fire pot and below the same and a smoke pipe connected with said eduction pipe below the level of said fire pot, substantially as described.

2. In a hot air furnace, a fire pot and a combustion chamber terminating in an imperforate dome, means for injecting air into the upper end of said dome, a smoke eduction pipe leading from said combustion chamber below said dome and extending downwardly on the outside of said fire pot and below the same, a smoke pipe connected to said eduction pipe adjacent the lower end thereof, said eduction pipe being extended 10 below the point of connection with the smoke pipe and forming a soot chamber and a clean-out door for said soot chamber, substantially as described.

In testimony whereof I have signed my 15 name to this specification.

OSCAR W. ANDERSON.
